W. BOLLHEIMER.
STARTER FOR EXPLOSIVE ENGINES.
APPLICATION FILED FEB. 26, 1919.

1,331,798.

Patented Feb. 24, 1920.

UNITED STATES PATENT OFFICE.

WILLIAM BOLLHEIMER, OF DAYTON, OHIO.

STARTER FOR EXPLOSIVE-ENGINES.

1,331,798.

Specification of Letters Patent. Patented Feb. 24, 1920.

Application filed February 26, 1919. Serial No. 279,372.

To all whom it may concern:

Be it known that I, WILLIAM BOLLHEIMER, citizen of the United States, residing at Dayton, in the county of Montgomery and State of Ohio, have invented certain new and useful Improvements in Starters for Explosive-Engines, of which the following is a specification.

This invention relates to starting or cranking devices for explosive engines, commonly known as self starters when applied to motor vehicles, for which purpose the present device is particularly adapted, although also applicable to stationary engines.

15. The object of the invention is to simplify the structure as well as the means and mode of operation of such devices, whereby they will not only be cheapened in construction, but will be more efficient in use, positive in 20 action, reliable in operation, easily manipulated and unlikely to get out of repair.

A further object is to provide means for automatically and instantly releasing the actuating element, in the event of "back fire" 25 or premature explosion, at any mid stroke position of the actuating element.

A further object is to provide such a device which may be easily and quickly installed upon existing automobile or other 30 explosive engines, without materially changing or modifying any of the parts thereof.

A further object is to provide a device which will impart to the crank shaft of the engine a quick initial movement with minimum effort of the operator, and to provide 35 improved means for automatically disengaging the actuating element at the limit of its stroke in either direction.

With the above primary and other incidental objects in view as will more fully appear in the specification, the invention consists of the features of construction, the parts and combinations thereof, and the mode of operation, or their equivalents, as 45 hereinafter described and set forth in the claims.

Referring to the drawings, Figure 1 is a perspective view, somewhat diagrammatic, showing the relative location and arrangement of the parts of the starting device forming the subject matter hereof upon an automobile. Fig. 2 is a front elevation of the starting mechanism. Fig. 3 is a rear elevation thereof. Fig. 4 is a side elevation,

viewed from the left of Fig. 2. Fig. 5 is a 55 vertical sectional view.

Like parts are indicated by similar characters of reference throughout the several views.

In the drawing the vehicle has been illustrated by dotted lines in Fig. 1 in which 1 is the body of the vehicle, 2 the hood, 3 the radiator and 4 the chassis frame bars. Portions of the vehicle have been shown broken away to disclose within the starting 60 apparatus forming the subject matter hereof. The starting apparatus is operated entirely independent of the usual starting crank 5, which, however, is left mounted in its bearing 6, ready for use in any emergency.

In applying the apparatus to the motor of a vehicle of the type shown in Fig. 1, and known as a Ford automobile, the original fan belt pulley found upon the engine shaft 75 is removed, and a sleeve 8 is substituted therefor surrounding which is a substitute fan belt pulley 9. The sleeve 8 is counter-bored at its inner end to receive the end of the engine crank shaft, beyond which the 80 sleeve 8 extends. The sleeve and substitute fan belt pulley 9 may be secured to the crank shaft in any suitable manner, such as by a transverse pin 10. The sleeve 8 is reduced in diameter a short distance forward 85 of the fan belt pulley 9 and at its forward extremity is provided with a series of clutch teeth 11 for engagement of the crank 5 for emergency use. Fixedly secured upon the sleeve 8 and abutting upon the shoulder 90 formed by the reduction of the diameter of the sleeve is a ratchet wheel 12. Loosely journaled upon the projecting portion of the sleeve 8 and adjacent to the ratchet wheel 12 is an actuating member comprising a hub 95 portion 13, a channeled rim 14 and an arm 15 connecting the rim and hub portions. The hub portion 13 has been shown provided with a bearing bushing 16. The actuator is secured in position by a split ring or 100 collar 17 sprung into a peripheral groove in the extended end of the sleeve 8.

The actuator is oscillated about the sleeve 8 by means of a flexible connection 18, which may be a chain or a cable, passing about the 105 channeled periphery of the segmental rim 14 to which it is attached at 19, thence over suitable guide pulleys 20 and 21 to an operating

lever 22 located in proximity to the driver's position. The operating lever 22, may be either manual or pedal operated, and may be of any desired construction. That shown in Fig. 1 is one commonly employed for this purpose. The preferred form of actuating mechanism is that by which the actuating element is given a uniform impulse at each operation.

- 10 Pivoted to the rear side of the arm 15 of the actuating element is a pawl 23, provided with a spring 24, which normally tends to oscillate the pawl 23 into engagement with the teeth of the ratchet wheel 12.
- 15 As shown in the drawing, the ratchet pawl 23 is somewhat triangular in form. It is obvious however, that this shape of the pawl is not essential. The pawl is actuated by the spring 24, into engagement with the 20 ratchet 12, at the beginning of the stroke of the actuator and is automatically disconnected from the ratchet 12 at the limit of such stroke. To effect this disengagement at either limit of the stroke of the actuating 25 member and also at any intermediate position, there is provided upon this pawl 23, a projecting stud carrying a roller 25, which extends into the plane of operation of an arcuate movable cam bar 26. The cam bar 30 26 is preferably pivoted at 27 to any suitable support such as the engine casing, or in the case of the Ford engine, it may be attached to the timer bracket, which is conveniently located for this purpose. The arcuate cam bar 35 at its free end rests upon the edge of the pan or guard, which extends beneath the crank shaft. Cam faces 28 and 29 are provided upon the outer or upper periphery of the arcuate cam bar 26, with which the anti-friction roller 25, carried by the pawl 23, engages at either limit of its stroke, whereby the pawl 23 is oscillated about its pivotal connection 23^a with the arm 15, to disengage the pawl from the ratchet 12. This serves 40 to automatically disengage the pawl at either limit of its stroke, and to hold the pawl out of engagement with the ratchet between successive operations.

One of the primary objections to starters 50 of this type heretofore devised has been the danger and the breakage of parts incident to a premature explosion, or backfire of the engine, whereby the motor crank shaft is rotated in reverse direction, or in opposition 55 to the movement of the starter while the latter is engaged therewith. To overcome this difficulty, means are herein provided for automatically disengaging the pawl 23 from the ratchet 12 at any mid-stroke point in the event of any such premature explosion or the reversal of the direction of rotation of the motor shaft. To this end the cam lever 26 is provided with an upward extending fixed arm 30 adjacent 60 to its free end, to which fixed arm 30 is

pivoted at 31^a a swinging arm 31, having thereon a cam face 32, extending into the path of travel of the anti-friction roller 25, and also having a detent finger 33 engaging with the teeth of the ratchet wheel 12, over 70 which the detent finger rides idly so long as the ratchet is rotated forwardly under the influence of the pawl 23. As the actuating element approaches the forward limit of its stroke, and the anti-friction roller 25 75 engages the cam face 29 by which the pawl is lifted out of engagement with the ratchet wheel 12, the roller 25 engages the cam face 32, of the swinging arm 31, oscillating said arm about its pivotal connection 31^a, against 80 the tension of a spring 34 to likewise withdraw the detent finger 33 from engagement with the ratchet wheel 12. The operated position of the pawl 23 and the swinging arm is shown by dotted lines in Fig. 3. In 85 the event however of a premature explosion or backfire, whereby the crank shaft of the motor and the ratchet wheel 12 carried thereby, are rotated in a reverse direction, the ratchet wheel 12 by the engagement of the detent finger 33 therewith, tends to elevate the arcuate cam bar 26 about its pivotal connection 27, causing the curvilinear face of the bar intermediate the cam faces 28 and 29 to engage the anti-friction 90 roller 25, of the pawl 23, at any mid-stroke position at which the pawl may be found at the moment of backfire, and so lift the pawl 23 against the tension of its spring 24, out of engagement with the ratchet wheel 12, 100 A stop lug 35, carried by the swinging cam bar 26, serves to limit the movement of the swinging arm 31 toward the ratchet wheel 12, under the influence of the spring 34. As the cam bar 26 is elevated under the influence 105 of the detent finger 33, upon reverse rotation of the ratchet 12, thereby disengaging the actuating pawl 23, the actuating element will advance idly, immediately to its forward position, whereupon the engagement of the anti-friction roller 25 with the cam faces 29 and 32, will automatically disengage and hold both the detent finger 33 110 and the actuating pawl 23, out of engagement with the ratchet wheel 12. This disengaging movement occurs instantaneously 115 upon the reversal of the ratchet 12. The ratchet 12 by its reverse movement elevates the intermediate portion of the cam bar 26 into the path of the roller 25, thus freeing 120 the pawl 23, and permitting the actuator to advance instantly to the limit of its stroke, thereby freeing the detent finger 33, thus preventing breakage of the pawls or the ratchet teeth and avoiding the danger incident 125 to the violent projection of the operative lever 22 rearward or toward the operator, while the operator's hand or foot is engaged therewith.

From the above description it will be ap- 130

parent that there is thus provided a device of the character described, possessing the particular features of advantage before enumerated as desirable but which, obviously, is 5 susceptible of modification in its form, proportions, detail construction and arrangement of parts, without departing from the principle involved or sacrificing any of its advantages.

10 While in order to comply with the statute, the invention has been described in language more or less specific as to structural features, it is to be understood that the invention is not limited to the specific details 15 shown, but that the means and construction herein disclosed, comprise but one of several modes of putting the invention into effect, and the invention is therefore claimed in any of its forms or modifications within 20 the legitimate and valid scope of the appended claims.

Having thus described my invention I claim:

1. A starter for internal combustion engines wherein a ratchet wheel operatively connected with the crank shaft of the engine is intermittently engaged by a pawl carried by an oscillatory carrier to which an oscillatory movement is given by suitable operating means, characterized by an arcuate movable bar normally positioned concentric with the path of travel of the pawl and means operated by the reversal of direction of rotation of the shaft to move the arcuate 35 bar to eccentric position in the path of travel of the pawl for automatically disengaging said pawl at any point in the stroke of said carrier upon a reverse movement of the engine shaft.

40 2. A starter for internal combustion motors of that character embodying a ratchet operatively connected with the crank shaft of the motor, an oscillatory pawl carrier mounted adjacent to the ratchet, a pawl 45 carried thereby and arranged to engage the teeth of the ratchet and an operating element for the pawl carrier, characterized by a cam bar extending between the limits of the stroke of said pawl and having cam surfaces thereon engaged by the pawl at either 50 limit of its stroke whereby the pawl is disengaged from the ratchet.

55 3. A starter for internal combustion motors comprising, a ratchet operatively connected with the motor shaft, an oscillatory pawl carrier mounted adjacent thereto, a pawl carried thereby and adapted to operatively engage with said ratchet, means for oscillating the carrier, a normally stationary trip member and means operated by the reversal of the direction of rotation of the shaft to actuate the trip member for disconnecting the pawl from the ratchet at indeterminate points in its path of travel.

60 65 4. A starter for internal combustion en-

gines wherein a ratchet operatively connected with the motor shaft is operated by a pawl carried by an oscillatory pawl carrier actuated at the will of the operator, characterized by a normally stationary cam 70 member movable into the path of travel of the pawl for disengaging the actuating pawl at any mid stroke position by the reverse operation of the motor.

5 A starter for internal combustion engines, wherein a ratchet operatively connected with the motor shaft is operated by a pawl carried by an oscillatory pawl carrier actuated at the will of the operator, characterized by a pawl disengaging element 75 normally inoperative to disengage the pawl in mid stroke position, a second pawl carried thereby engaging said ratchet and adapted upon reversal of the normal direction of movement of the ratchet to move 80 said disengaging element to operative position.

6 A starter for internal explosive engines wherein a ratchet operatively connected with the engine shaft is operated by 90 a pawl carried by an oscillatory pawl carrier actuated at the will of the operator, characterized by a normally stationary disengaging element, adapted to disengage the pawl at either limit of its stroke, and means to 95 automatically shift said disengaging element to effect the disengagement of the pawl in a mid stroke position.

7 A starter for internal combustion engines wherein a ratchet operatively connected with the engine shaft is operated by 100 a pawl carried by an oscillatory pawl carrier actuated at the will of the operator, characterized by a second pawl also engageable with said ratchet from which it is 105 disengaged upon movement of the ratchet in one direction, the second mentioned pawl being adapted to effect the disengagement of the first mentioned pawl upon a reverse movement of the ratchet.

8 A starter for internal combustion engines wherein a ratchet operatively connected with the engine shaft is operated by a pawl carried by an oscillatory pawl carrier actuated at the will of the operator, 110 characterized by a movable pawl disengaging element normally positioned out of the mid stroke path of travel of the pawl, and means controlled by the movement of the ratchet for shifting the disengaging element into the mid-stroke path of the pawl whereby the pawl will be disengaged from the ratchet.

9 A starter for internal combustion engines wherein a ratchet operatively connected with the engine shaft is operated by a pawl carried by an oscillatory pawl carrier actuated at the will of the operator, characterized by a single disengaging member having thereon cam faces projecting into the 120 125 130

- path of travel of the pawl at either limit of its stroke adapted upon engagement by said pawl to lift the pawl out of engagement with the ratchet.
- 5 10. A starter for internal combustion engines wherein, a ratchet operatively connected with the engine shaft is operated by a pawl carried by an oscillatory pawl carrier actuated at the will of the operator, characterized by a pivoted lever having cam faces thereon engaged by said pawl at either limit of its stroke to disengage the pawl from the ratchet, a second pawl carried by

said lever and engaging said ratchet whereby upon a reverse movement of the ratchet 15 the lever will be oscillated to disengage the first mentioned pawl at a mid stroke position.

In testimony whereof, I have hereunto set my hand this 11th day of February A. D. 20 1919.

WILLIAM BOLLHEIMER.
